S. SIMONSON.

YOKE FOR RAILWAY DRAFT GEARS.

APPLICATION FILED MAY 7, 1918.

1,352,151.

Patented Sept. 7, 1920.

UNITED STATES PATENT OFFICE.

SIGVARD SIMONSON, OF BUTLER, PENNSYLVANIA, ASSIGNOR TO HARRY VISSERING & COMPANY, OF CHICAGO, ILLINOIS, A CORPORATION OF ILLINOIS.

YOKE FOR RAILWAY DRAFT-GEAR.

1,352,151.

Specification of Letters Patent. Patented Sept. 7, 1920.

Application filed May 7, 1918. Serial No. 233,021.

To all whom it may concern:

Be it known that I, SIGVARD SIMONSON, a citizen of the United States, and a resident of Butler, in the county of Butler and State 5 of Pennsylvania, have invented certain new and useful Improvements in Yokes for Railway Draft-Gears, of which the following is a full, clear, and exact description.

The invention relates to railway draft-gear yokes.

One object of the invention is to provide a one-piece forged yoke which comprises side-members having their front ends formed to be keyed to a coupler shank and 10 an integral connection at the back, the sides having transversely alined openings therein adapted to receive laterally the draft-gear. Such a construction makes possible, in a one-piece yoke, direct transmission of the 15 pulling stresses from the front ends of the sides to the back of the yoke which is centrally disposed with respect to the rear follower-plate or rear of the draft-gear, and this characteristic is attained by forming 20 openings in the integral side-members so that portions of the latter will over and underlie the shock-absorbing device.

A further object of the invention is to provide a one-piece yoke whereby the pulling 25 stresses will be directly transmitted from the front portions of the yoke to the back by rearwardly converging tension members so that compressive stresses only will be exerted by the yoke upon the rear follower plate, as 30 contra-distinguished from bending moment resulting from application of the stresses to a follower plate laterally of the draft-gear. This result is attained by forming the yoke 35 of convergent integral sides with a narrow connecting back therebetween and having openings in the sides to receive and retain the draft-gear.

A further object of the invention is to provide an improved draft-gear yoke which is 40 simple in construction and efficient to withstand maximum stresses with a given weight of metal.

Other objects of the invention will be apparent from the detail description.

The invention consists in the several novel 50 features hereinafter set forth and more particularly defined by claims at the conclusion hereof.

In the drawings: Figure 1 is a plan of a

railway draft-gear embodying the invention, parts being shown in section. Fig. 2 is a longitudinal section of the draft-yoke and connected parts, some of which are shown in elevation. Fig. 3 is a perspective of the yoke. Fig. 4 is a transverse section 60 on a line 4—4 of Fig. 2.

The invention is illustrated as applied to a railway draft-gear comprising a coupler 65 disposed between a pair of draft-beams 10, a key 11 extending through the coupler shank and elongated slots 11^a in the draft-beams, a draft-gear 14, of any suitable construction, interposed between the front and rear follower-plates 15 and 16, front stops 12 and rear stops 13, as well understood in the 70 art, and the improved yoke hereinafter described. A plate 17 may be used to sustain the rear of the yoke.

The improved yoke comprises integral sides 18 and 19 and a curved connecting 75 back 20. The yoke is of such construction that it can be forged and formed of a bar comprising top and bottom flanges 21 and 22 and a vertical connecting web 23 which has a rib or thickened central portion 24, 80 and thin portions extending from the outer face of the flanges to the inner margins of the rib 24. Adjacent the front end of each yoke-side, a transverse slot 25 is formed and the metal at the front of these slots is swaged 85 or upset, as at 26, to reinforce the front end of the key-slot. The key 11 extends through slots 25 to secure the yoke to the coupler shank. An opening 30 is formed in the web 23 and between the top and bottom flanges 90 of each yoke-side. Each of these openings is of sufficient length and height for the lateral insertion of the follower plates 15 and 16 and the draft-gear 14. The front follower plate 15 is adapted to engage the 95 front, and the rear follower plate 16 is adapted to engage the back edges of openings 30 in the yoke-sides. The front edges and the rear edges of these openings are inclined from the tops and bottoms to a vertical central surface 31, to cause the yoke to be engaged by the follower plates substantially at the center of the yoke and to centralize the applied stresses on these plates for substantially even distribution to the 100 ends of the draft-gear. This formation results in holding the follower-plates truly and avoids contacting surfaces adjacent the

105

top and bottom portions of these plates, which, in practice, cause distortion of the plates. The thickened portion 24 of the web 23 reinforces the back-edges 31 which engage the rear follower plate, and also reinforces the entire back of or integral connecting portions between the yoke-sides. The metal in front of openings 30 is forged to form reinforcement 26 around and in front 10 of the key-slots and is flattened between said openings and said reinforcement to leave clearance between the front stops 12 and the outer faces of the yoke-sides. A saddle plate 35 bears on the lower convergent draft members of the yoke and holds the draft gear against displacement.

The method of forging the improved yoke is exemplified and claimed in an application filed by me May 7, 1918, Serial No. 20 233,022 for the method of making said yokes.

The front ends of the one-piece yoke are separated sufficiently to receive the coupler-shank, and the sides converge from the front 25 portions to the semi-circular integral back connection 20. Forming the openings 30 for the draft-gear and follower plates in the yoke-sides, as shown, leaves each side with upper and lower connecting members 30 between the front and back which are disposed to vertically clear the draft-gear, so that the sides and these bars may converge to centrally apply the pulling stresses to the rear follower plate. Since these tension 35 members are spaced apart sufficiently so that portions of the shock-absorbing device may be disposed in and project outwardly through the sides of the yoke, it becomes possible to sufficiently converge these members from the front of the yoke, where they 40 are keyed to the coupler to cause the stresses to be directly transmitted from the key and front end of the yoke to the central portion of the back follower-plate and through it to 45 the draft-gear.

The invention exemplifies a one-piece yoke which has integral sides with openings adapted for transverse insertion of the draft-gear and follower plates. Also a one-piece yoke with convergent sides which have members or portions disposed above and below the draft-gear and follower plates and whereby the pulling stresses are applied in the direction of said draft-members to the 50 back of the yoke where they are centrally applied to the rear follower plate without bending moment upon said plate. Also one which is adapted to be forged and in which the necessity of riveting or locking a plurality of side-members together is avoided. The invention also exemplifies a yoke in 60 which the tensile strength of metal is fully utilized to render the yoke efficient in use.

The invention is not to be understood as 65 restricted to the details set forth, since these

may be modified within the scope of the appended claims, without departing from the spirit and scope of the invention.

Having thus described the invention, what I claim as new and desire to secure by Letters Patent, is:

1. A draft-gear yoke consisting of a forging having sides and a connecting back integral with said sides, the latter having their front ends separated and formed for 75 keying to the coupler shank and having longitudinally extending openings therein between the back and the front ends adapted for the lateral insertion of the draft-gear.

2. A draft-gear yoke consisting of a forging of general U shape, having openings through the members thereof between the front and rear ends to permit the insertion and removal of the draft-gear laterally, and leaving a vertical rear portion arranged to 85 lie behind the rear follower plate and forward web portions lying in front of the front follower plate, said front portions being formed for keying to the coupler shank, the members being disposed laterally of one 90 another and the back forming a horizontal connection therebetween.

3. A draft-gear yoke consisting of a forging having sides and a connecting back integral with said sides, the latter having their 95 front ends spaced apart laterally and formed for keying to the sides of the coupler shank and having longitudinally extending openings between the back and the front ends for the draft-gear, said sides being rearwardly convergent relatively to each 100 other for centralized application of the stresses to the back of the draft-gear.

4. A draft-gear yoke consisting of a forging having sides disposed laterally of one 105 another and a back integral with said sides, the latter having their front ends spaced apart laterally and formed for keying to the coupler-shank, and openings therein between the front ends and the back, each side 110 having upper and lower longitudinal members above and below the openings respectively and formed to over and underlie the draft-gear.

5. A draft-gear yoke consisting of a forging having sides disposed laterally of one 115 another, and rearwardly divergent relatively to each other and a back integral with said sides, the latter having their front ends spaced apart laterally and formed for keying to the coupler shank and openings therein between the front ends and the back, each side having upper and lower longitudinal members above and below the openings respectively and formed to over and underlie the draft-gear.

6. A draft-gear yoke of general U shape consisting of a forging having a rear portion or column arranged to lie behind the back follower plate, two front web portions 130

- arranged to lie in front of the front follower plate and respectively on the two sides of the coupler shank, and four draft members arranged in pairs symmetrically with reference to the longitudinal axis of the draft-gear, the upper draft members of each pair being integral extensions from the upper end of the rear portion and from the top edges of the two front web portions and the lower draft members of each pair being integral extensions from the lower end of the rear portion and from the lower edges of the two front web portions, the upper and lower draft members of each pair lying respectively above and below the draft-gear to permit the insertion and removal of the draft-gear laterally, and said front web portions being provided with means for keying to the coupler shank.
7. A draft-gear yoke consisting of a forging having a narrow rear portion or column arranged to lie behind the back follower plate, two front web portions arranged to lie in front of the front follower plate and respectively on the two sides of the coupler shank, and four draft members arranged in pairs symmetrically with reference to the longitudinal axis of the draft-gear, the upper draft members being integral extensions from the upper end of the rear portion and from the upper edges of the front web portions and the lower draft members being integral extensions from the lower end of the rear portion and from the lower edges of the front web portions, the front web portions being provided with means for connection to the coupler shank, said pairs of draft members diverging in a straight line from the narrow rear portion to the front web portions, whereby the draft stresses are applied directly through the integral structure to the rear portion of the yoke, the upper and lower draft members of each pair lying respectively above and below the draft gear to permit the insertion and removal of the draft-gear laterally.
8. A draft-gear yoke consisting of a forging having sides disposed laterally of one another and a connecting back integral with the sides, top and bottom inwardly extending flanges on the sides and back and a connecting web between the flanges, the sides having longitudinal openings therein for draft-gear and having their front portions spaced apart laterally and formed for keying to the sides of the coupler-shank.
9. A draft-gear yoke consisting of a forging having sides disposed laterally of one another and a connecting back integral with the sides, top and bottom inwardly extending flanges on the sides and back and a connecting web between the flanges, the sides having openings therein for the lateral insertion of the draft-gear and having their front portions spaced apart laterally and formed for keying to the sides of a coupler-shank, said web having a thickened zone in the rear of said openings.
10. A draft-gear yoke consisting of a forging having sides disposed laterally of one another and a back, the sides having their front portions spaced apart laterally and formed for attachment to the coupler-shank and having openings therein for the insertion and removal of the draft-gear, the ends of the openings having central bearing surfaces and being inclined away from said surfaces.
11. A one-piece draft yoke consisting of a forging having a rear portion arranged to lie behind the back follower plate, forward portions spaced apart laterally and lying in front of the front follower plate and at the sides of the coupler shank and provided with means for attachment to the latter, a pair of draft-members disposed laterally of one another connecting the upper end of the rear column with the upper portions of the forward side members respectively and lying above the draft-gear, a pair of draft-members disposed laterally of one another connecting the lower end of the rear column with the lower portions of the forward side members respectively and lying below the draft-gear, and a saddle plate resting on the two bottom draft-members and supporting the draft-gear.

SIGWARD SIMONSON.
